UNITED STATES PATENT OFFICE

1,999,104

TELEPHONE INSTALLATION

Friedrich Merk, Frankfort-on-the-Main,
GermanyApplication February 24, 1934, Serial No. 712,825
In Germany February 25, 1933

17 Claims. (Cl. 179—18)

This invention relates to multiple connection systems for telephone installations and is intended to provide certain new and useful improvements in mechanisms of this character and class.

In my co-pending patent application Serial No. 656,731 filed February 14th, 1933, now Patent No. 1,972,199, of Sept. 4, 1934, a multiple connection system for telephone installations is set forth having selectors and lines subdivided into groups in which provision is made for mutual assistance of the selector groups, in that the lines of one group, in addition to being multiplied to one selector group, are also similarly multiplied to another selector group. Each selector group thus contains two similarly formed partial multiples, the combination of which is different from selector group to selector group.

The invention is concerned with a connection system for connectors to the multiple of which, in accordance with the invention, two groups of subscriber's lines are connected. In this case, the lines of a group of 100 subscriber's lines are connected to the first partial multiple of the selectors of a group of connectors which are selected by the characteristic figure of this group of 100 in the preceding group selectors. The lines of this group of 100 are, however, in addition connected to the second partial multiple of the selectors of one or more other groups of connectors which are selected by other characteristic figures in the preceding group selectors. In this way, all the lines in the second partial multiple of the neighbouring groups of connectors can be connected, or by sub-division of the group of 100 lines into sub-groups, each of these sub-groups can be alternatively connected to different groups of connectors.

With this connection system for connectors, the problem now arises that the preceding group selectors after selection of a group of connectors must make a further group selection movement for the auxiliary operation in order to be able to seize a connector to the second partial multiple of which the desired subscriber's line is also connected. For the solution of this problem, the invention provides that when the connectors of a group are not available, those connectors are made inaccessible to preceding group selectors so that the preceding group selectors are prevented from hunting over the connectors of this group. This at the same time makes the preceding group selectors suitable for being set on another group of connectors to the second partial multiple of which the desired line is connected.

A further feature of the invention is to make possible the setting of the connector on the contacts of its second partial multiple. For this purpose, the invention provides for changing the connector on initiation of the auxiliary operation.

In order that the invention may be thoroughly understood and be more readily carried into effect, some examples of construction in accordance therewith will now be described with reference to the accompanying drawings. In these examples of construction there is a selector having a flat bank multiple and a multiple brush switch member moving to and fro in front of its rows of contacts. During the setting, this switch member moves downwards under the influence of its own weight. The invention is, however, in no way restricted to the use of special selectors but can be used also with other selectors of other types.

Figure 1 shows diagrammatically a multiple brush selector for 100 lines;

Figure 2 shows a similar selector for 200 lines;

Figure 3 is a circuit diagram for a connection between a subscriber's set and a current impulse repeater through a call finder arranged between them;

Figures 4 and 5 are respectively the circuit diagrams for a group selector for 100 and 200 lines which, when the desired group of connectors is made inaccessible, is stepped on to the next group of connectors.

Figure 6 is the circuit diagram for a connector of 200 lines which can co-operate with the group selector of Figures 4 and 5.

Figure 7 is the circuit diagram for a group selector for 200 lines which when the desired group of connectors is made inaccessible, selects another group of connectors in accordance with the tens digit of the desired subscriber's line.

Figure 8 is a circuit diagram for a connector for 200 lines which can co-operate with a group selector according to Figure 7.

The selector multiple of Figure 1 consists of five partial banks V, each having two groups of lines which are indicated by the references 1 and 6, 2 and 7 and so forth on the right hand side. Each group of lines contains 10 lines. A switch member S having five sets of brushes B and a push rod T is diagrammatically shown on the left hand side of the selector multiple. Similar switch members can also be arranged on the other side of the multiple. The switch member as illustrated is in the position of rest in which the free ends of the brush springs B which make the contact are

separated from the contacts of the group of lines which they serve by increasing amounts which, expressed in terms of switching steps, are indicated by the references $y2 \dots y6$. The brush sets

- 5 B are normally separated from the contacts and are only brought towards them when one of the levers H is temporarily actuated by a finger F of the above mentioned push rod T. There are two fingers F for each lever H and the distances between a lever H and its appropriate actuating fingers F increase progressively. The distances between the levers H and the first fingers F which act on them expressed in terms of switching steps are indicated on the left of Figure 1 by the references $x1, x2 \dots x5$. The distance between a pair of fingers F is equivalent to five switching steps and this distance is indicated in Figure 1 by the references $z5$.

During the downward movement of the switch member S the sets of brushes arrive in sequence opposite the contacts of the first group of lines reached by them and also the working points of the levers H arrive in sequence opposite the finger F which is the first to be reached. When the switch member S is moved further, the brush sets arrive in sequence opposite the second finger F of a pair so that each set of brushes can be brought into use in two positions.

The arrangement for a selector multiple of twice the size of that shown in Figure 1 is shown in Figure 2 and will be seen to be fundamentally the same. This multiple comprises 10 partial banks V whose groups of lines are indicated by the references 11 and 21 ; 12 and 22 ; and so forth on the right, while the switch member S has 10 sets of brushes B and the push rod T has 10 sets of 2 fingers F. The distance between two fingers F in a pair is equivalent in this case to 10 switching steps and is denoted in Figure 2 by the reference $z10$. It is to be noted that in the inoperative position shown in Figure 2 the switch member is one switching step higher than in Figure 1. Therefore, the distances of the brush sets from their contacts with which they first engage and also the distances of the working points of the levers H from the fingers F are by one switching step greater than in Figure 1 and have therefore been denoted in Figure 2 respectively by the references $y3, y4 \dots y12$ and $x2, x3, x4 \dots x11$.

50 The switch member is released for the setting movements by a pawl controlled by an electromagnet which engages with a rack connected to the brush switch member. These movements can, according to the duration of the energization of the magnet, be step by step or continuous movements. The push rod is actuated by the intermittent actuation of a control switch (not shown in the drawings) when this switch passes through a position determined by an appropriate electromagnet. An auxiliary switch member, again not shown in the drawings, which at times moves with the brush switch member after a set of brushes has been made effective, is also provided in the selector. A selector with such an auxiliary switch member is described in Patent 1,895,265.

70 The circuits will now be described for various cases. In the following descriptions, the contacts of the above-mentioned rack are denoted by the reference k , the contacts of the control switch by the reference m and the contacts of the auxiliary switch by the reference n . These contacts, similarly to the others, are shown in the position of rest. The figures added to the reference letters k, m and n indicate the switch position in which 75 these contacts are actuated.

When the receiver at the subscriber's set TN shown in Figure 3 is lifted, the subscriber's line is connected through a call finder AS, in a manner known in itself, to an installation for repeating current impulses and speech. The relays A and Q are thus energized and the circuit is closed through the outgoing lines a, b, c . Owing to the numerical selection, the current impulse relay A swings so that the relay V responds and is held operated together with the relay Q for the duration of the series of current impulses. When the relay A again responds after the first release of its armature, the first current impulse proceeds over the following circuit:—

5 +, marking contact v , condenser K , marking contact and line a , setting magnet F of a subsequent selector (Figure 4), —.

This circuit includes a condenser in order to restrict the current impulses to a particular length which guarantees a step by step setting of the selector and thus makes it possible to use a setting magnet for the selector which has no large current strength. At each release of the relay A, the condenser K is discharged through a resistance w . During the transmission of each series of current impulses, a current also flows through the circuit:—

10 +, marking contact v , the second transformer winding, the line b , a control magnet S of the following selector (Figure 4), —.

(1) The 100-line group selector shown in Figure 4 can co-operate with the 200-line connector shown in Figure 6. In order that the switching steps may be best understood, the Figures 4 and 6 should be placed side by side.

15 Two groups of 100 subscribers' lines are connected to the connector of Figure 6. The first group of 100 is arranged in the first partial multiple of the connector, while the other group of 100 is connected to the second partial multiple of the connector. In order to be set on the contacts of this second group of 100 lines, the line selector must after the selection of the brush set corresponding to the group of 10, make an additional setting movement of 10 switching steps. 20 The multiple connection of the double groups of subscribers' lines through the individual connectors is, in this example of construction, carried out in such a way that the group of 100 lines connected to the first partial multiple of a group of connectors is also connected to the second partial multiple of the next group of connectors in the direction in which the group selection proceeds. Thus, if there is no connector of a particular group of connectors available for the connection, then the preceding group of selectors according to Figure 4 must be again connected to the following group of connectors for the auxiliary operation. The group selector illustrated in Figure 4 is constructed on the principle of that illustrated in Figure 1. It has in addition, however, a group testing brush gp which during the first setting movement of its switch member, wipes over a contact bank to the contacts of which a group testing line g is connected for any group of connectors to be selected.

25 When the current impulse repeater shown in Figure 3 operates and the relay Q has responded, the relay C in the group selector of Fig. 4 is energized. As already described, on the first release of the relay A of the current impulse repeater of Figure 3, the relay V is energized and thereby the b-wire of the connecting line is connected to the battery by means of the contact v . This 30 35 40 45 50 55 60 65 70 75 80 85 90 95 100

causes the magnet S of the control switch in the group selector of Figure 4 to be energized. The control switch is so constructed that at each energization and de-energization, it causes the control switch to be stepped through one step. During the sending out of a series of current impulses, the control switch magnet S remains energized by means of the b-wire so that the control switch is in the position 1. The current impulses sent out through the a-wire act on the stepping magnet F of the group selector and cause a step-by-step setting movement of the switch member. If, for example, three current impulses are sent, then the third brush from the top of the group selector comes in front of the beginning of the third contact field. At the end of the first series of current impulses, the relay V of the current impulse repeater again releases and interrupts the circuit for the control switch magnet S so that the latter releases and the control switch is stepped into the position 2. In this position 2, a contact 1m2 of the control switch is closed and thus the winding I of a relay U and the group testing brush gp of the selector is connected to the control switch magnet S. There are two different cases which will be separately considered:

(a) If a connector of a selected group of connectors is available for the making of a connection, then the group testing line g in the line selector is connected through the contacts 1k1—31 and 4c' to the positive terminal of the battery. The winding I of the relay U is thus short circuited on closing of the control switch contact 1m2 by means of the group testing line and cannot respond. The control switch magnet S responds, however, in the circuit formed by the group testing line g and steps the control switch into the position 3 out of which the control switch immediately moves into the position 4 because there is no energizing circuit for the magnet S in the position 3. Owing to the passing of the control switch from the position 3 to the position 4, the push rod T mentioned in the description of Figure 1 is mechanically rotated for a short time so that the set of brushes selected by the first setting movement of the group selector is influenced by the appropriate finger F and is made effective for making contact. At the same time, an auxiliary switch is coupled to the switch member and partakes of the further movement of the switch member.

In position 4 of the control switch, an energizing circuit for the setting magnet F is now closed:

— magnet F, contacts 3k1—31, 4m4—10, 3n16, 2p, +.

In this circuit, the setting magnet F is continuously energized and releases the switch member for carrying out a uniform movement.

At the same time, the control switch is also moved forward into the position 5, because the magnet S is energized through the contacts 3m4 and 1k1—5. The control switch immediately passes from the position 5 into the position 6 because the magnet S is not held energized in the position 5.

As soon as the brush of the group selector which has been made effective arrives on the contact of a free connector of the selected group of connectors, the relay P responds in the following testing circuit:

+, contact 1n1—10, contact 5m5—6, both windings of relay P, contact 3c, testing brush, line c,

contact 2k1—31 of the line selector of Figure 6, relay C' —.

The relay P short circuits its high resistance winding with the contact 1p in the known manner and thus makes the selected connector inaccessible. The contact 2p interrupts the energizing circuit of the setting magnet F so that the switch member is brought to rest on this contact.

If, by means of the first setting movement of the group selector, the third line selector group was not selected by three numerical current impulses, but for example, the 6th connector group was selected by means of six numerical current impulses, then as has already been explained by means of Figure 1, on the passing of the control switch from the position 3 to the position 4, the uppermost set of brushes of the group selector would be made effective by the temporary actuation of the push rod T. This set of brushes is, however, still at a distance of five switching steps from the sixth contact bank of the group selector to which the desired group of connectors is connected. The switch member of the group selector must thus first make an additional movement of five switching steps before the testing can take place of the contacts wiped over by the set of brushes. For this purpose, the control switch remains in the position 4 while the switch member is displaced by the numerical current impulses through more than five switching steps because the contact 1k1—5 is open. The energizing circuit for the setting magnet F, as in the previously described case, is closed. The testing circuit is, however, closed through the contact 2n6—15 only on the sixth step of this uniform movement of the switch member so that thus the five contacts of the contact bank 1 of the group selector are run over idly.

With the energization of the relay P, the relay C' in the connector of Figure 6 is also energized. At the beginning of the further current impulse transmission, the b-wire in the current impulse repeater of Figure 3 is again connected to the battery so that the control switch magnet S' of the connector of Figure 6 is energized through the contacts 4p and 4m4—10. As the contact 6m2—10 of the group selector is open, the control switch magnet S of the group selector is not influenced. The control switch magnet S' is energized, closes its contact s' and steps the control switch into the position 1.

The current impulses run again through the a-wire. The setting magnet F of the group selector is not influenced, because the contact 7m2—10 of the group selector is open. On the other hand, the numerical current impulses act on the setting magnet F' of the connector and cause a step-by-step setting of the switch member. If, for example, five current impulses are sent out, then at the end of the series of current impulses, the fifth set of brushes of the connector is in front of the fifth contact bank. At the end of the series of current impulses, the control switch magnet S' is again devoid of current and causes the control switch to be switched again into the position 2. On the transference from the position 1 to the position 2, the push rod T of the line selector is temporarily operated so that the selected 5th set of brushes is influenced and is made effective for making contact. At the beginning of the second series of current impulses, the control switch magnet S' is again energized by the b-wire and switches the control switch into the position 3. The current impulses act again on the setting magnet F' through the closed

contact s' ; at the end of the current impulse transmission, owing to the de-energization of the control switch magnet S' , the control switch proceeds to the position 4 and by means of the contact 5 tact 2m4 closes the testing circuit through the relay P' . The control switch is immediately further switched from the position 4 into the position 5 and closes the following circuit:

+, contacts 1y, 1c', 3m4—5, magnet S' , —.

- 10 It is then held in that position by the continuous energization of the magnet S' . The testing thus takes place only during the transference of the control switch from the position 4 to the position 5. If the line is free and the relay P' has responded, then the calling current is sent out through the closed contact 2s' of the control switch magnet. The alternating calling current runs through the windings of the relay Y which, however, cannot respond to the alternating current because the lower winding is short-circuited by the contacts 2s'. As soon as the called subscriber answers, direct current flows in the known manner through the windings of the relay Y . The relay Y is energized, interrupts the energization of the control switch magnet S' with its contact 1y so that it is released, switches out the calling current with the contact 2s' and switches the control switch into the position 6.

15 The breaking of the connection is independent of the calling subscriber. The steps involved, however, have nothing to do with the present invention.

20 (b) The case will now be considered in which when the group selector is set on the third group of connectors, there is no connector in this group which is available for the further selection. In this case, the contacts 1k1—37 and 4c' in all connectors of this group are open. The group testing line g is thus disconnected. As soon as 25 the control switch of the group selector has moved after the first series of current impulses into the position 2, the relay U is energized by the winding I which is not, as in the preceding case, short circuited by the group testing line g .

25 The relay U responds, together with the control switch magnet S and by means of the contact 1u of its winding II closes a holding circuit.

The contact 2u energizes the setting magnet F and sets up the circuit:

30 +, contact 2m2, contact 2u, magnet F .

35 This results in the switch member being lowered through a further step. The energization of the magnet F lasts only for a short time as the magnet S is energized at the same time as the relay U and switches the control switch into the position 3, out of which it passes into the position 4 owing to the fact that the relay S is no longer energized. When the control switch passes from the position 3 to the position 4, the push rod 40 T of the group selector is again temporarily actuated. Although the switch member is lowered through three switching steps by the first setting movement of the group selector, the fourth set of brushes from the top is now influenced because, indeed, the contact 2u causes the switch member to be stepped through a further step. Thus, not the brush set which is associated with the desired third group of connectors, but the brush set which is associated with the fourth group of connectors is made effective. The desired group of 100 subscribers' lines is connected to the second partial multiple in this fourth group of connectors.

45 The selection of a free line in this group of connectors takes place as previously described.

50 When a free line is found, the relay P responds by means of the contact 1p, makes the seized connector inaccessible and by means of contacts 3p and 4p connects the speech wires. The contact 2p thus causes the release of the setting magnet F and the release of the relay U . The relay U is constructed so as to be slow to release and thus still holds its contact 3u closed when the contact 3p is closed. As a result, a relay U' is energized in the seized connector of Figure 6 and the following circuit is set up:

55 +, contact 3u, contact 3p, group selector brush, line a, contact 5m4—10, contact 1s', winding I of relay U' , —.

60 The relay U' lies with its contact 2u' of its winding II in a holding circuit which runs through the contact 1c' of the relay C' which has been energized in the meanwhile.

65 At the beginning of the next series of current impulses, as described, the control switch magnet S' of the connector is energized by the b-wire. The current impulses act on the setting magnet F' which, on energization of the control switch magnet F' , is connected by the contact 1s' to the a-wire. After the current impulse transmission, the control switch magnet S' releases and switches the control switch into the position 2. When the control switch passes from the position 1 to the position 2, the push rod T of the connector is again actuated for a short time and 70 makes the set of brushes selected by the first setting movement effective for making contact. At the same time, the auxiliary switch member is coupled to the switch member. In the position 2 of the control switch, the following energizing circuit for the setting magnet F' of the connector is closed:

75 +, contact n10—37, 1u', 1m2, magnet F' . The magnet F' attracts its armature and thus releases the switch member for a continuous 80 movement. As soon as the switch member 10 has made 10 steps, the contact n10—37 opens, the setting magnet F' again becomes devoid of current and the switch member stops. The selected set of brushes is thus stepped through 10 85 switching steps. If, by means of the first setting movement, the fifth set of brushes was, for example, selected and thus made effective, then this set of brushes is now in front of the contact bank 25 (Figure 2) of the second partial multiple. 90

95 The next series of current impulses sent out by the subscriber switches the switch member into the position 3 of the control switch. At the end of the series of current impulses, as already described, the testing takes place in the position 4 of the control switch and the calling current is sent out in the position 5.

100 As is obvious, when the group of connectors to the first partial multiple of which the desired subscribers' line was connected is made inaccessible, hunting over the selectors of this group was prevented in the group of selectors arranged in front of it by energization of the relay U . The group selector was, moreover, automatically stepped on to the next group of connectors and immediately a free connector is seized in the following group of connectors, this seized connector is provided with a "change" characterization through a speech wire. The "change" characterization was stored in a relay U' of the connector and, after carrying out the tens selection through the connector, has stepped the connector on to the contacts of the second partial multiple to which the desired subscriber's line is also connected. This storing of the "change" character- 105

ization can naturally also be carried out by switch means belonging to the group selector which transfer the characterization to the connector only after transmission of the series of current impulses necessary for the tens selection.

(2) The group selector illustrated in Figure 5 is made for 200 lines and can co-operate with the connector shown in Figure 6. The arrangement and operation will be best understood by placing the two circuit diagrams one beside the other. The construction of the connector of Figure 5 corresponds substantially with that diagrammatically illustrated in Figure 2. There are 10 sets of brushes and 20 groups of contacts 11-20. In addition, a further group testing brush *gp* is, however, provided which is moved during the group selection movement over a bank of 20 contacts to which one group testing line *g* is connected for each group of line selectors.

(a) If a connection is to be made to one of the groups of connectors 11-20, then the series of current impulses acting first of all on the group selector consists of only one current impulse. On the seizing of the current impulse repeater of Figure 3, the relay *C* of the group selector is energized. At the beginning of the transmission of a series of current impulses, the *b*-wire in the current impulse repeater is connected to the battery by the contact *v*, so that the switching magnet *S* is energized and moves the control switch into the position 1. The current impulses act on the setting magnet *F*. If the first series of current impulses only comprises, as assumed, one current impulse, then the switch member is lowered through one step and then the control switch magnet *S* is de-energized so that the control switch is moved into the position 2.

At the beginning of the next sequence of current impulses, which also acts on the group selector, the control switch magnet *S* is again energized and switches the control switch into the position 3. The current impulses then influence the setting magnet *F*, while at the end of the sequence of current impulses, the control switch moves into the position 4 by the de-energization of the control switch magnet *S*. If five current impulses are sent out in this second sequence of current impulses, then the fifth set of brushes of the group selector now finds itself in front of the contact of the group of connectors 15. In the control switch position 4, the contact *3m4* is closed and thus both the winding *I* of the relay *U* and also the group testing brush *gp* are connected to the control switch magnet *S*.

(b) Before the further switching steps are described, it will be briefly explained how the setting of the group selector on one of the line selector groups 11-20 takes place. In this case, the first series of current impulses which acts on the group selector consists of two current impulses. While the control switch is in the position 1, the switch member is thus lowered through two switching steps and, in this case, the contact *1k2-10* is closed. This causes the energization of the setting magnet *F* in the following circuit:

+ contact *2m1*, contact *1k2-10*, magnet *F*, -. The magnet *F* responds and releases the switch member of the selector for a uniform movement. During this energization of the setting magnet *F*, the control switch is held in the position 1 by the energization of the magnet *S* in the following circuit:

+ contact *1m1*, contact *f*, magnet *S*, -. At the eleventh setting step of the switch member, the contact *1k2-10* is again opened and the

setting magnet *F* becomes devoid of current and holds the switch member in this position. Through this lowering of the switching member through 10 switching steps, the second series of fingers *F* on the push rod *T* shown in Figure 2 is now brought into operation for making effective the set of brushes to be selected by a second series of current impulses. After this automatic further switching movement of the switch member, the control switching magnet *S* again becomes devoid of current and brings the control switch into the position 2, out of which it moves into the position 3 at the beginning of the second series of current impulses acting on the group selector. By means of this second series of current impulses, the setting magnet *F* is again energized step by step. At the end of the second series of current impulses, the control switch magnet *S* releases as a consequence of the interruption of the circuit existing owing to the *b*-wire and causes the further switching of the control switch into the position 4. If this second series of current impulses consists of five current impulses, the fifth set of brushes of the group selector is now in front of the contact of the group of connectors 25.

(c) If a connector of the selected group of connectors is free, then the group testing line *g* is connected to the battery. With the closing of the contact *3m4*, the winding *I* of the relay *U* of the group selector is then short circuited. Only the control switch magnet *S* is energized and switches the control switch into the position 5 out of which it moves immediately into the position 6 owing to the absence of further energization of the magnet *S*. On the transference from the position 5 to the position 6, the push rod (Figure 2) is temporarily actuated and makes the selected set of brushes effective for making contact. At the same time, the auxiliary switch member is coupled to the switch member so that it partakes of the further setting movement of the switch member. Through the contact *1m6*, the following energizing circuit for the setting magnet *F* is closed:

+ contacts *2p*, *1n11*, *1m6*, *3k1-37*, magnet *F*, -. 45

The magnet *F* responds and releases the switch member for a uniform movement. This movement is limited to 10 switching steps because, on the eleventh step, the contact *1n11* opens. Immediately a free connector is found during the wiping over of the 10 contacts of a group of connectors, the relay *P* responds in the following circuit:

+ contact *2n1-10*, both windings of relay *P*, testing brush, line *c*, *2k1-37*, relay *C'*, -. 55

The relay *P* interrupts the energizing circuit for the setting magnet *F* by means of its contact *2p* and thus stops the switch member of the group selector. The connector is made inaccessible by the contact *1p* by short circuiting of the high resistance winding of the relay *P*, while the contacts *3p* and *4p* connect the speech wires. The setting of the connector according to Figure 6 now occurs in the manner already described. 65

(d) If there is no connector of the selected group of connectors available, then the group testing line *g* is disconnected. On the closing of the contact *3u4* in the group selector (Figure 5), the relay *U* is energized through its winding *I* together with the control switch magnet *S*. The relay *U*, by means of the contact *1u*, closes a holding circuit for its winding *II* and by means of contact *2u* energizes the setting magnet *F* for a short time in the following circuit: 70

+, contact 4n4, contact 2u, setting magnet F, —.

This energization is immediately interrupted because the control switch is moved into the position 5. The brief energization of the setting magnet F results in the lowering of the switch member through a further step. Thus, as soon as the control switch has moved from the position 5 to the position 6 as a consequence of the absence of energization of the magnet S, not the set of brushes selected by the numerical current impulses, but the set of brushes corresponding to the next group of connectors will be made effective for making contact. In the position 6 of the control switch, the automatic hunting of the group selector starts again and this is ended by the response of the relay P when a free connector of this neighboring group of connectors is found.

20 By the opening of the contact 2p, the de-energization of the winding II of the relay U is de-energized, in addition to the group selector being stepped. The relay U is made slow to release and thus holds its armature attracted for some time. On the connection of the speech wires by means of the contact 3p and 4p, the following energizing circuit for the relay U' of the connector of Figure 6 is thus set up:

+, contact 3u, contact 3p, brush of the group selector, a-wire, contact 5m4—10, contact 1s', winding I of the relay U', —.

The relay U responds and, in the already described fashion, stores this "change" characterization for the connector. By means of the next series of current impulses, the connector is set for the selection of the tens group of the subscribers' line. For this purpose, the relay U carries out in the described fashion the automatic further switching of the connector through ten switching steps on to the contacts of the second partial multiple to which the desired subscriber's line is connected. The last series of current impulses then makes the final setting of the selected brush sets on to this subscriber's line.

45 (3) The group selector illustrated in Figure 7 is made for 200 lines and co-operates with the line selectors of Figure 8. The line selectors of Figure 8 are also made for 200 lines and receive in their first partial multiple the lines of a group of 100 subscribers' lines, while to the second partial multiple, the lines of several groups of 100 subscribers' lines are connected alternating from group of 10 to group of 10. These groups of 100 subscribers' lines are thus subdivided into separate sub-groups of 10. To the first sub-group of 10 of the second partial multiple of the connector, are connected the lines of the first sub-group of 10 of the first partial multiple of the next following group of connectors. To the second sub-group of 10 of the second partial multiple of the connectors are connected the lines of the second sub-group of 10 of the first partial multiple of the next group but one of connectors. The distance of the groups of connectors in which the individual sub-groups of 10 are connected to the first or the second partial multiple thus increases with the characterizing digit of the sub-group of 10.

70 This type of multiple connection of the subscriber's lines in the connectors makes it necessary that the group selectors should be switched over for the auxiliary operation to various other groups of connectors when the selector of the selected group of connectors is not available, according to which characterizing digit of the sub-

group of 10 of the desired subscribers' line is being dealt with. If the subscriber's line lies with the first sub-group of 10, then the preceding group selector must, in auxiliary operation, be stepped on to the next succeeding group of connectors. If the subscriber's line lies in the second sub-group of 10, then the group selector must be switched on to the next group of connectors but one and if the subscriber's line is in the 10th sub-group of 10, then the group selector must be stepped on to the 10th group following the selected group of connectors. In order that the group selector must be thus stepped onto the different groups of connectors, it is made for 200 lines.

As the stepping of the group selector in auxiliary operation occurs in dependence upon the characterizing digit of the tens group of the subscriber's line, that is to say, in dependence upon the current impulses which are to set the connector on the sub-group of 10, storing switch means must be provided in the group selector which store up these current impulses and, after the seizing of a connector in auxiliary operation, again transmit to the connector. Preferably, these storing devices are so constructed that they can receive both the series of current impulses sent out for the selection of the sub-group of 10 and also for the selection of the individual line. The storing devices can be associated in common with the selectors of a group selecting unit as they are only used in the rare case of auxiliary operation. In the connection system of Figure 7, the storing devices and the group selectors are individually associated. For any series of current impulses to be stored, a storing switch arrangement is provided controlled by two magnets D and E. The relays U, B and J are also, however, associated with this storing switch arrangement.

(a) The steps arising in the general case when a connection is made will now be explained. When the current impulse repeater of Figure 3 is seized, the relay C of the group selector of Figure 7 responds so that the relays B and U are energized through the contact 4c. At the beginning of the current impulse transmission for setting the group selector, the b-wire in the current impulse repeater of Figure 3 is connected to the battery by means of the contact v so that the control switch magnet S responds and the control switch switches into the position 1. The current impulses sent out through the a-wire energize a relay A' step by step which effects the step by step energization of the setting magnet F with its contact a' in the following circuit:

+, contacts 1a', 2n11, 2p, magnet F, —. The switch member lowers through as many switching steps as there are current impulses acting on the group selector. At the end of this series of current impulses, the control switch magnet S releases owing to the fact that the b-wire becomes devoid of current and switches the control switch into the position 2 in which the contact 1m2 is closed and connects the control switch magnet S to the group testing brush gp. Since, as assumed, there is a free connector in the selected group, the group testing line g is connected to the battery through the contacts 1k1—37 and 4c'. The control switch magnet S is energized and switches the control switch into the position 3 out of which it moves into the position 4 owing to the absence of energization of the control switch magnet S. On the transfer from the position 3 to the position 4, the push rod T actuates, which makes

the set of brushes selected by the first series of current impulses effective for making contact. At the same time, the auxiliary switch member is coupled to the switch member. Through the contact $5m4-10$, the following energizing circuit for the setting magnet F is closed:

+, contacts $6m4-10$, $2n11$, $2p$, magnet F, -.

The setting magnet is energized and releases the switch member for uniform movement.

10 This movement is limited to ten switching steps by the contact $2n11$. At the same time, the control switch magnet is energized through the contact $5m4$ so that the control switch moves into the position 5 and out of this position, owing to the absence of energization of the magnet S, into the position 6. In the position 6, the control switch magnet S is energized through the contact $7m6$ and steps the control switch into the position 7 out of which it is again switched, due to the absence of energization of the magnet S, into the position 8, in which the speech lines are connected by the contacts $11m8$ and $12m8$ while the control switch magnet and the relay A' are disconnected from the speech wires by the contacts $9m6-10$ and $10m6-10$.

When the selected set of brushes arrives on the contact of a free connector, the relay P responds in the circuit:

+, contact $1n1-10$, both windings of relay

30 P, contact $3c$, testing brush of the group selector, c-wire, contact $2k1-31$, relay C', -.

The relay P short circuits its high resistance winding with the contact $1p$ and thus makes the seized connector inaccessible. At the contact $2p$, the circuit for the setting magnet F is interrupted so that the latter releases and stops the switch member. The contacts $3p$ and $4p$ connect the speech wires. In the connector, the relay C' responds in the testing circuit. At the beginning of the next sequence of current impulses, the control switch magnet S' of the connector is energized by the b-wire and switches the control switch into the position 1. At the same time, the contact $1s$ is closed. The current impulses transmitted through the a-wire act on the setting magnet F' of the connector. At the end of the series of current impulses, the magnet S' releases and switches the control switch into the position 2. On transfer from the control switch position 1 to the position 2, the push rod T is temporarily actuated and makes the set of brushes selected by the first current impulse transmission effective. At the beginning of the second series of current impulses, the control switch magnet S' is again energized through the b-wire and switches the control switch into the position 3 while at the same time closing the contact $1s'$. The current impulses again act on the setting magnet F'. At the end of the current impulse transmission, the control switch goes into the position 4. In the position 4, the testing circuit for the relay P is closed by the contact $2m4$. The contact $3m4-5$ at the same time closes a new energizing circuit for the control switch magnet S' so that the control switch moves into the position 5 in which the control switch magnet S' is held energized. If the relay P has been able to respond through the contacts of a free subscriber's line, then the line is made inaccessible by the contact $1p'$ by short circuiting of the high resistance winding, while the contacts $2p'$ and $3p'$ connect the speech wires. The sending out of the calling current now occurs through the contact $2s'$. As soon as the called subscriber

replies, a direct current flows through the winding of the relay Y, the relay Y responds and with the contacts $2y$ and $3y$ connects the speech wires.

(b) The case will now be considered in which there is no connector available in the desired group of connectors. When the current impulse repeater is seized, the relay C is again energized in the group selector (Figure 7) and also the relays B and U connected up thereby. During the first current impulse transmission, the control switch magnet S is energized through the b-wire and holds the control switch in the position 1. The current impulses running through the a-wire influence the relay A' which with its contact $1a'$ transmits the current impulses to the setting magnet F. If, for example, five current impulses are sent out, then the switch member of the selector is lowered through five switching steps so that the fifth brush set finds itself in front of the contact field of the group 15 (Figure 2). At the end of the series of current impulses, the control switch magnet S is devoid of current so that the control switch moves into the position 2. If, as is assumed, there is no connector 25 of this group which is available, then the group testing line g is disconnected and the control switch magnet S cannot be energized by the contact $1m2$.

If now the current impulses sent out by the subscriber which, in normal operation, serve for setting the connector on the tens group of the subscriber's line, then these current impulses act again on the group selector. At the beginning of the series of current impulses, the control switch magnet S is again energized through the b-wire and moves the control switch into the position 3. The current impulses transmitted through the a-wire are now transmitted by the relay A' first by means of a contact $1a'$ to the setting magnet F 40 and secondly by means of the contact $2a'$ to the setting magnet DI of the first storing switch device. This storing switch device is so constructed that a switch member is displaced step by step by a setting magnet DI while a force is stored, 45 that is to say, against the action of a spring or gravity. The switch member is also influenced by an electromagnet E, the armature of which controls an escapement which, on attraction and repulsion of the armature, releases the switch member for a movement amounting to half a switching step so that after a setting by the setting magnet DI, it is returned by alternate energizations and deenergizations of the electromagnet EI by half switching steps back into its normal position, under the action of the previously stored force. 55

The switch member of the storing switch device I is also displaced step by step during the further displacement of the switch member of the group selector. If the desired subscriber's line lies for example in the ninth sub-group of ten of a group of 100 subscriber's lines, then nine current impulses are transmitted in this series of current impulses so that the switch member of the group selector is lowered through nine further switching steps. At the end of this movement, the fourth set of brushes from the top of the group selector thus lies in front of a finger F of the second series of fingers on the push rod T so 70 that after a temporary actuation of the push rod, the contact field 24 can be wiped over. The group of connectors 24 which is separated by nine group selection steps from the first selected group of line connector 15 is connected to this contact 75

field 24 as, from the assumed multiple connection, the ninth sub-group of the 100-group 15 is connected to the second partial multiple of the connector which in the preferred operation, serves the 100-group 24. If, for example, there are only 10 groups of connectors, then in this contact group 24, the lines which lead the group of connectors 15 are, however, repeated because the assumed multiple connection of the subscriber's lines to the first and second partial multiples of the connectors is made cyclically through all the groups of connectors present.

At the end of the series of current impulses which transmits the characteristic digit of the tens sub-group of the desired subscriber's line, owing to the de-energization of the control switch magnet, the control switch moves into the position 4. On the transfer from the position 3 into the position 4, the push rod T is temporarily actuated so that thus the selected fourth set of brushes of the group selector is now made effective for making contact. Owing to the displacement of the storing switch device by means of the setting magnet DII, the contacts 1wI, 2wI and 3wI are also thrown. The contact 1wI has the effect of preventing an energizing circuit for the control switch magnet from being closed in the control switch position 4 and the control switch thus then remains in the position 4. On reaching the control switch position 4, an energizing circuit for the setting magnet F of the group selector is immediately closed through the contact 6m4—10, the magnet F responds and releases the switch member of the group selector for a uniform movement. This movement is limited to 10 switching steps by the contact 2n11 as the auxiliary switch member which controls the contacts n was coupled to the group selector switch member on the transfer of the control switch from the position 3 to the position 4. The selected set of brushes is thus moved on by the contacts of the contact group 24. As soon as the set of brushes finds a free connector, the following testing circuit is closed:

45 +, contact 1n1—10, both windings of the relay P, contact 3c, testing brush, c-wire, 2k1—37, relay C' of the connector, —.

The relay P responds, makes the seized connector inaccessible by closing the contact 1p, interrupts the energizing circuit for the setting magnet F of the group selector with the contact 2p and connects the speech wire with the contacts 2p and 4p.

As soon as the contact 3p is closed, the following circuit for the setting magnet F' of the connector is set up:

46 +, contacts 1wI, 1u, 3m4, 3p, brushes of the group selector, a-wire, contact 3k1—37, contact 4m4—10, magnet F' —.

The setting magnet F' is energized and releases the switch member of the connector for a uniform movement. After the first switching step of this switch member, the energizing circuit for the setting magnet is broken at the contact 3k1—37. The electro-magnet F is, however, maintained energized in the circuit:

47 +, contacts 1y, 1c, 1m1—10, f', contact 5k1—37, magnet F', —, until this circuit is interrupted at the 10th switching step. By the setting of the storing switch device I in the first group selector, the connector will be stepped through ten steps immediately after being seized so that the brushes of the connector come in front of the contacts of the second partial multiple. This "change"

takes place through an energization of the setting magnet without previous energization of the control switch magnet, that is to say, in the control switch position 0.

In the group selector, the control switch finds itself during these switching steps in the position 4. If now the current impulses corresponding to the units digit of the desired subscriber's line are sent out by the subscriber, then the control switch magnet S is energized again by the b-wire so that the control switch is transferred into the position 5. The current impulses running through the a-wire are now transmitted through the relay A' only to the setting magnet DII of a second storing switch device. The setting magnet F of the group selector can no longer be influenced by these current impulses because the relay P is energized. The setting magnet DII of the second storing switch device is actuated step by step and the storing switch device moves through as many switching steps as there are current impulses which have been transmitted. At the end of the current impulse transmission, the control switch magnet releases in consequence of the interruption of the circuit running through the b-wire and switches the control switch into the position 6. With the setting of the second storing switch device, the contacts 1wII and 2wII are reversed. In the control switch position 6, the energizing circuit for the relay B is interrupted at the contact 8m6—10. The energizing circuit for the relay U is, however, maintained by the contact 2wI and the resistance wI. The relay B allows its armature to release and closes the contact b.

At the same time, in the control switch position 6 there is an energizing circuit for the control switch magnet S' of the connector:

48 +, contacts 1wI, 1u, 13m6—10, 4p, brushes of the group selector, b-wire, contact 4m4—10, 40 magnet S', —.

The control switch magnet of the connector is energized and brings the control switch into the position 1.

By the closing of the contacts b, the electro-magnet EI is energized in the circuit:

49 +, contacts b, i, 2u, 3wI, magnet EI, —.

The magnet EI responds, closes the contact eI and returns the switch member of the storing switch device I through half a step. The relay J is energized by the contact eI and reverses its contact i and thus closes the following energizing circuit for the setting magnet F' of the connector of Figure 8:

50 +, contacts b, i, 3p, brushes of the group selector, a-wire, contact 1s', contact 5m4—10, magnet F', —.

By the reversal of the contact i, the energizing circuit for the magnet EI of the storing switch device I is at the same time interrupted, so that the latter releases and the switch member of the storing switch device is again released for half a step. Owing to the release of the magnet EI, the relay J is, however, also devoid of current. In this alternating operation of the magnet EI and of the relay J, the switch member of the storing switch device is thus at times released for a return movement of half a switching step, while for the carrying out of a whole switching step, a current impulse is sent out to the a-wire. 70 The setting magnet F' of the connector receives thus as many current impulses as there are current impulses stored by the storing switch device through the series of numerical current impulses sent out for characterization of the tens group. 75

If, as assumed, nine current impulses are stored, then after return of the storing switch member I into its position of rest, the switch member of the connector is lowered through nine further switching steps so that the ninth set of brushes is in front of the contacts of the ninth group of 10 of the second partial multiple.

By the return of the storing switch device I into the position of rest, the contacts wI are again reversed. The circuit running through the b-wire for the control switch magnet S' is interrupted at the contact $1wI$ so that the control switch of the connector is transferred into the position 2, the push rod T is thus temporarily actuated and the ninth set of brushes of the connector is made effective for making contact. The contact $2wI$ interrupts the energization of the slow to release relay U.

As soon as after a given time the relay U has allowed its armature to release, the following energizing circuit for the control switch magnet S' of the connector is closed:

+ contacts $1wII$, $1u$, $13n6$ —10, 4p, brushes of the group selector, b-wire, contact $5m4$ —10, control switch magnet S' —, so that the control switch of the line selector is transferred into the position 3. At the same time, the following energizing circuit for the magnet EII of the second storing switch device is closed by the contact $2wII$:

+ contacts b , 1 , $2u$, $2wII$, magnet EII , —.

This magnet EII also co-operates with the relay J so that the set switch member of the second storing switch device II is returned in half switching steps into its position of rest, while at the same time, after each full switching step, a current impulse is transmitted to the setting magnet F' of the connector through the a-wire. The switch member of the connector is thus lowered through as many switching steps as there are current impulses which have been sent out for characterizing the units digit and the desired subscriber's line. After return of the storing switch device II into its position of rest, the contacts wII are reversed. The contact $1wII$ interrupts the circuit through the b-wire so that the control switch of the connector is transferred into the position 4. At the same time, the contact $1wII$ closes the following energizing circuit for the control switch magnet S of the group selector:

+ contact $1wII$, contact $1m6$, magnet S , —, so that the control switch is transferred into the position 7 and immediately out of this position into the position 8 owing to the absence of energization of the control switch magnet S , in which position the speech lines are connected through the contacts $11m8$ and $12m8$.

In the position 4 of the control switch of the connector, the testing circuit for the relay P' is closed through the contact $2m4$. The control switch is at the same time transferred to the position 5 by energization of the magnet S' through the contact $3m4$ —5 in which position the magnet S' is maintained energized. If the subscriber's line is free, then the relay P' responds, makes the desired subscriber's line inaccessible by means of the contact $1p$ and switches the calling current on to the speech wires by means of the contact $2p$ and $3p$ which runs over the contact $2s'$ and the windings of the relay Y. As soon as the subscriber replies, the relay Y is energized by the direct current flowing through the windings of the relay Y, interrupts the circuit for the control switch magnet S' by opening its contact $1y$ so that the latter releases, interrupts

the calling current by means of the contact $2s'$, and steps the control switch into the position 6. The contacts $2y$ and $3y$ connect the speech wires.

It will be seen that in this example in which the lines of a group of 100 subscriber's lines are connected from sub-group to sub-group to the second partial multiple of different groups of connectors, storing switch means are associated with the group selectors which allow the current impulses serving for the characterizing of the sub-groups and the characterizing of the units digit of the desired subscriber's line to be stored. The changing over of the connector for auxiliary operation is carried out immediately after the seizing of a free connector.

It is immaterial for the invention whether both series of current impulses necessary for setting the connector are stored in the group selector. The arrangement can be so designed that in the group selector only the current impulses characterizing the tens group which are sent out immediately after the seizing of a free connector are stored so that the units current impulses act directly on the connector.

In the described example, the group selector is, for the auxiliary operation, stepped through as many group selection steps as there are current impulses which have been sent out for characterizing the tens group of the desired subscriber's line. The storing switch means of the group selector are thus made as simple current impulse repeaters. The multiple connection of the subscriber's lines can naturally also be carried out in other ways, for example, so that the lines of the tenth sub-group of 10 of a group of 100 subscriber's lines are arranged in the second partial multiple of the neighbouring group of connectors and the lines of the first sub-group of 10 of this group of 100 subscriber's lines are connected to the second partial multiple of the connector group, 10 group selection steps away. In this case, it is necessary to provide in the group selector for a translation of the stored current impulses.

In the described examples, the characterization for changing of the connector for auxiliary operation is always carried out from the preceding group selector in dependence upon the inaccessibility of a particular group of connectors from this group selector. This sort of "changing" of the connector is not absolutely essential, as it is moreover also possible when all the connectors of a group are unavailable to change over directly to auxiliary operation, for example, through a call distributing connection from this group of connectors to a connector of another group to the second partial multiple of which the desired subscriber's line is connected and to use the step of making a group of connectors inaccessible which acts backwards on the preceding group selector only for preventing the hunting of the group selector over the inaccessible group of connectors and for making possible the stepping of the group selector.

I claim:

1. A telephone installation comprising in combination connectors sub-divided into groups and subscriber's lines divided into groups, said connectors in each group forming two like partial multiples, a connection between each two groups of subscriber's lines, and said two partial multiples of each of said connector groups, a group selector adapted to select said groups of connectors and to seize a free connector within the selected group, means for making said group of

connectors inaccessible from said group selector when all connectors of said group to the first partial multiple of which the desired line is connected are unavailable, said means being adapted 5 to prevent the initiation of hunting by said group selector over the connectors of said group and being adapted to make said group selector suitable for selecting another connector group to the second partial multiple of which the desired line 10 is also connected.

2. A telephone installation comprising in combination connectors subdivided into groups and subscriber's lines subdivided into groups, said connectors in each group forming two like partial multiples, a connection between each group of subscriber's lines and the first partial multiple of a group of said connectors and to the second partial multiple of another of said groups of connectors, a group selector adapted to select a desired group of said connectors and to seize a free connector within the selected group, means for making inaccessible said group of connectors from said group selector when all connectors of said group are unavailable, said means being adapted 15 to prevent the initiation of hunting by said group selector over the connectors of said group to the first partial multiple of which the desired subscriber's line is connected and means for stepping said group selector onto a group of connectors to the second partial multiple of which said group of subscriber's lines which contains the desired subscribers' line is connected, said stepping means being controlled by said first mentioned means.

3. A telephone installation according to claim 2, wherein group testing means are provided within the group selector which are adapted to prevent the initiation of hunting by said selector over the connectors of a selected group of connectors rendered unavailable and in which the stepping means of the group selector are controlled by said group testing means.

4. A telephone installation comprising connectors subdivided into groups and subscriber's lines subdivided into groups, the connectors of each group forming two like partial multiples, the lines of each group of subscriber's lines being connected to the first partial multiple of a group of connectors and to the second partial multiple of another group of connectors, means for "changing" the connectors, said means influencing the connectors for being set onto lines connected to said second partial multiple, said means being controlled when all connectors of a group of connectors to the first partial multiple of which the desired subscriber's line is connected are unavailable.

5. A telephone installation comprising connectors sub-divided into groups and subscriber's lines sub-divided into groups, the connectors of each group forming a "first" partial multiple and a "second" like partial multiple, the lines of each group of subscriber's lines being connected to the "first" partial multiple of a group of connectors and to the "second" partial multiple of a second group of connectors, the connectors of each group being adapted to be set onto a line of its "first" partial multiple and to be set onto a line of the "second" partial multiple by stepping the selector brushes, means for "changing" a connector of a group of connectors to the second partial multiple of which the desired line is connected, said changing means influencing the connector for being set onto lines of its "second" partial multiple by stepping the selector brushes, said means

being controlled when all connectors of a group of connectors to the first partial multiple of which the desired line is connected are unavailable.

6. A telephone installation comprising in combination, connectors subdivided into groups and subscriber lines subdivided into groups, said connectors in each group forming two like partial multiples, a connection between each group of subscriber's lines and the first partial multiple of a group of said connectors and to the second partial multiple of another of said groups of connectors, the connectors of each group being adapted to be set onto a line of its "first" partial multiple and to be set onto a line of its "second" partial multiple, means for "changing" the connectors, said means being associated with the connectors and adapted to influence the connectors for being set onto lines connected to said second partial multiple, a group selector adapted to select a desired group of connectors and to seize a free connector within the selected group, said selector having group testing means for preventing the initiation of hunting by said group selector over the connectors of the selected group when all connectors of said group are unavailable, and said selector having further means for stepping said group selector onto a group of connectors to the second partial multiple of which the desired subscriber's line is connected, and having means for transmitting a "change" characterization to a seized connector, said stepping means and said transmitting means being controlled by said group testing means.

7. A telephone installation according to claim 6 wherein the "changing" means of the connectors are controlled by the transmitting means of the group selectors.

8. A telephone installation according to claim 6 wherein the "change" characterization is transmitted immediately upon the seizing of a free connector by said group selector and in which the said "changing" means influence the connector for being set onto lines connected to its second partial multiple after the setting of the connector under the influence of current impulses characterizing the tenth group of the desired line.

9. A telephone installation comprising connectors sub-divided into groups and subscriber's lines sub-divided into groups and sub-groups, the connectors of each group forming a "first" partial multiple and a like "second" partial multiple, both partial multiples being sub-divided into sub-groups, the lines of each group of subscriber's lines being connected to the "first" partial multiple of a first group of connectors and to the "second" partial multiple of another group of connectors, means for "changing" a connector to the "second" partial multiple of which the desired line is connected, said means causing the further switching of the connector onto the contacts of the "second" partial multiple, a group selector adapted to select the groups of connectors and to seize a free connector within the selected group, means for preventing an initiation of hunting by the said group selector when all connectors of the selected group of connectors to the first partial multiple of which the desired line is connected are unavailable, means controlled by said second mentioned means for stepping said group selector over a connector group to the partial multiple of which the desired line is connected, and said means for changing the connector being likewise controlled by said second mentioned means.

10. A telephone installation according to claim 9, in which said means for "changing" the con-

5 nector are controlled by said means for preventing the initiation of hunting by the group selector between the setting operations of the connector in dependence upon the current impulses characterizing the sub-group of the desired subscriber's line and upon the current impulses characterizing the desired line within the sub-group.

10 11. A telephone installation according to claim 9, in which the means for changing the connector are controlled by said means for preventing the initiation of hunting by the group selector through the speech wires of the line between the group selector and the selected connector.

15 12. A telephone installation according to claim 9, in which the means for changing a connector are controlled by the means for preventing the initiation of hunting by the group selector immediately upon the seizing of the said connector.

20 13. A telephone installation comprising in combination connectors sub-divided into groups, subscribers' lines sub-divided into groups, said connectors in each group comprising a "first" partial multiple and a "second" like partial multiple, said groups of subscriber's lines being subdivided into sub-groups, the "second" partial multiples of each of said groups of connectors being subdivided into sub-groups, all sub-groups of a group of subscriber's lines being connected to all sub-groups of the "first" partial multiple of a group of said connectors, the individual sub-groups of a group of subscribers' lines being also connected from sub-group to sub-group alternately to the "second" partial multiple of other different groups of connectors, a group selector adapted to select a group of connectors and to seize a free connector within the selected group, means for making a group of connectors inaccessible from said group selector when all connectors of said group to the first partial multiple of which the desired line is connected are unavailable, means for stepping said group selector over another group of connectors in dependence upon the current impulses sent out for selection of the

sub-group of subscriber's lines, said stepping means being controlled by said first mentioned means.

14. A telephone installation comprising in combination connectors sub-divided into groups, subscriber's lines sub-divided into groups and sub-groups, the connectors of each group forming a "first" partial multiple and a "second" like partial multiple, both partial multiples being subdivided into sub-groups, all sub-groups of a group of subscriber's lines being connected to all sub-groups of said "first" partial multiples of a group of connectors, the individual sub-groups of a group of subscriber's lines being connected in addition from sub-group to sub-group alternately to said "second" partial multiple of other subsequent groups of connectors, a group selector adapted to select the group of connectors and to seize a free connector within the selected group, means for preventing the initiation of hunting by said group selector when all connectors of the selected group of connectors to the "first" partial multiple of which the desired line is connected are unavailable, means for stepping the group selector in dependence upon the current impulses sent out for determining the sub-group of the subscriber's line, said means being controlled by said first mentioned means and means controlled by said first mentioned means for storing the current impulses for determining the sub-group of the desired subscriber's line.

15. A telephone installation according to claim 14, comprising storing means associated with said group selector for storing a plurality of sequences of current impulses.

35 16. A telephone installation according to claim 14, comprises storing means associated with all group selectors of a group selection unit.

17. A telephone installation according to claim 14 wherein said storing means are adapted to transmit the stored current impulses in the same number and sequence.

FRIEDRICH MERK.
